CLOCK DIAL

Andrew Eklund, New York, N. Y.

Application May 3, 1932, Serial No. 609,051

4 Claims. (Cl. 58—43)

This invention relates to a clock dial and has for an object to provide an improved clock dial which will serve not only for the purpose of telling local time, but also for the purpose of telling 5 the time at selective zones and cities throughout the whole world.

A further object of this invention is to provide a clock dial which will indicate to the observer the time of day or night in any other zone 10 or section of the world which corresponds to the prevailing local time.

Yet an additional object of this invention is to provide a clock dial, having a dial ring over which the clock hands pass to tell the local time, 15 and having a separate movable dial which will move in correspondence with the hour hand to indicate the time in other cities.

Still a further object of this invention is to provide means on this movable dial, which means 20 will not only serve to indicate the prevailing time in foreign or distant time zones, but which indicating means will always remain in an easily readable position, irrespective of the rotation of the dial.

25 Still a further object of this invention is to provide indicating means placed about the periphery of the revolving dial, which indicating means will always remain in an upright or level reading position, enabling the same to be easily 30 read, irrespective of the rotation of the supporting dial.

With the foregoing and other objects in view, as will hereinafter become apparent, this invention comprises the constructions, combinations 35 and arrangements of parts, hereinafter set forth, disclosed and shown on the accompanying drawing. In this drawing,

Figure 1 is a partly sectional view of the clock dial and operating mechanism,

40 Figure 2 is a plan view of the clock dial,

Figure 3 is a plan view of the blank for one of the zone plates,

Figure 4 is a plan view of the assembled zone plate, and

45 Figure 5 is a sectional view of the assembled zone plate.

There is shown at A a stationary dial ring around the surface of which are placed the numerals and divisions representing the hours 50 of the day in the usual manner.

The dial ring A is held stationary in an outer flange of a back plate B, which in turn is fastened to the frame C of the clock movement, not shown. An hour shaft E operated by the clock 55 mechanism, is provided for operating the hour

hand F about the dial ring A, and a shaft E' within the hour shaft E serves to operate the minute hand F' over the dial ring A in the usual manner.

A dial D is fastened on the outside of the hour 60 shaft E, as clearly shown in Figure 1, whereby the dial D partakes of the movement of the shaft E and hence of the hour hand F. The dial D will be of such diameter compared to the dial ring A, that the outer edge of the dial D will project 65 slightly under the inner edge of the dial ring A, as shown in Figure 1.

Spaced about the periphery of the dial D a plurality of time zone plates G are provided, one for each hour on the base of the dial ring A. 70 Each time zone plate G will have indicia thereon appropriate to two of the time zones on the world's surface, the time zones being each twelve hours apart. Although only a single city or country has been shown on several of the time 75 zone or dial plates G for each of the two zones, yet as shown on others of the dial plates G, two or more cities or countries may be shown for each zone on each dial plate G, this being merely a matter of appropriate selection. 80

The hour hand F and the minute hand F' extend across each of the time zone plates G successively during operation of the clock. In order to permit the successive time zone plates G to be visible, and especially, to permit the particular time zone plate G to which the hour hand F is pointing to be plainly visible while the hand F points thereto, the hour hand F and the minute hand F' are each provided with orifices f and f', the orifice f on the hour hand F and the orifice 85 f' on the minute hand F' each being of a diameter at least large enough to permit the inscription on the time zone plates G to be readable there- through.

Each dial plate G, as shown in Figures 3, 4 90 and 5, is made up of a blank of material folded over as at I, a supporting pin H having first been passed through the lower portion of the blank from which the plate G is formed. Except for the hinge portion I, the dial plate G is substan- 100 tially circular, but the depressed boss through which the supporting pin H projects is eccentric to the dial plate G so that plate G will hang suspended therefrom in the same position, irre- 105 spective of the revolution of the supporting pin H. The supporting pin H is mounted in the dial D at the appropriate position, so that the dial plate G will hang level as the dial D rotates with the hour hand F, and the indicia on the dial plate 110

G will always remain in the level and readable position.

A plurality of arrows J are provided on the dial D at each plate G, to cooperate with the 5 time marking on the dial ring A.

The novel features and the operation of this device will be apparent from the foregoing description. While the device has been shown and the structure described in detail, it is obvious 10 that this is not to be considered limited to the exact form disclosed and that changes may be made therein within the scope of what is claimed without departing from the spirit of the invention.

15 Having thus set forth and disclosed the nature of this invention, what is claimed is:

1. A clock comprising a pair of time hands and a clock dial comprising a dial ring having the hours indicated thereon, a dial rotatable 20 within the dial ring, a plurality of time zone plates mounted on the dial and cooperating with the dial ring, and means for mounting the time zone plates on the dial, whereby said time zone plates will remain in a level readable position 25 throughout the rotating of said dial, one of said hands extending across each of said time zone plates successively and an orifice in said hands larger than the time zone plate diameter permitting each time zone plate to be successively visible therethrough.

30 2. A clock dial comprising a dial ring having the hours indicated thereon, a dial rotatable within the dial ring, a plurality of time zone plates mounted on the dial and cooperating with the dial ring, means for mounting the time zone 35 plates on the dial, whereby said time zone plates will remain in a level readable position throughout the rotating of said dial, said means comprising an eccentrically placed depressed boss in each of said zone plates, and a pivot pin mounted 40 in said dial, said depressed boss being freely

mounted on said pivot pin, a pair of time hands mounted for operation over said clock dial, each time hand extending across said plurality of time zone plates, and an enlarged orifice in each time hand allowing a time zone plate to be readable therethrough.

3. In a clock having an hour hand shaft and a minute hand shaft, a dial ring on the clock having the hours indicated thereon, a dial mounted on the hour shaft to rotate therewith, the periphery of said dial slightly underlapping the inner periphery of said dial ring, a time arrow on said dial cooperating with an hour numeral on said dial ring, a time zone plate for said time arrow pivotally mounted on said dial, a minute hand on said minute hand shaft extending to said dial ring across the faces of said hour shaft dial and said time zone plate and an orifice in said minute hand of greater diameter than the time zone plate permitting said time zone plate to be readable therethrough.

4. In a clock having an hour hand shaft and a minute hand shaft, a dial ring on the clock having the hours indicated thereon, a dial mounted on the hour shaft to rotate therewith, 100 the periphery of said dial slightly underlapping the inner periphery of said dial ring, a time indicator on said dial cooperating with an hour numeral on said dial ring, and a time zone plate for said time indicator pivotally mounted on said 105 dial, there being one time zone plate for each hour numeral on the dial ring, each time zone plate having indicia thereon appropriate to different time zones on the world's surface, a minute hand mounted on said minute hand shaft and 110 extending to said dial ring to pass across the faces of each time zone plate successively during operation and an enlarged orifice in said minute hand permitting each zone plate to be successively readable therethrough.
